UNITED STATES PATENT OFFICE.

JOSEPH P. LAVIGNE, OF NEW HAVEN, CONNECTICUT, ASSIGNOR OF ONE-HALF TO WILBUR F. DAY, OF SAME PLACE.

BICYCLE-PEDAL.

SPECIFICATION forming part of Letters Patent No. 594,405, dated November 30, 1897.

Application filed February 10, 1896. Serial No. 578,649. (No model.)

To all whom it may concern:

Be it known that I, JOSEPH P. LAVIGNE, of New Haven, in the county of New Haven and State of Connecticut, have invented a new 5 Improvement in Bicycle-Pedals; and I do hereby declare the following, when taken in connection with the accompanying drawings and the letters of reference marked thereon, to be a full, clear, and exact description of 10 the same, and which said drawings constitute part of this specification, and represent, in—

Figure 1, a view, partly in plan and partly in section, of one form which a pedal constructed in accordance with my invention may 15 assume; Fig. 2, a similar end view thereof; Fig. 3, a detached view, in side elevation, of one of the plates; Fig. 4, a detached view in perspective of one of the rubber bars.

My invention relates to an improved pedal 20 for bicycles, the object being to produce a combined rat-trap and rubber-bar pedal adapted to be convertibly balanced so as to present uppermost to the foot either one foothold or the other, according to the disposition of the 25 rider or the dictation of circumstances, so that one pedal is made to combine the advantages of the two types of pedals, whereby an obvious gain in economy and convenience is effected.

With these ends in view my invention consists in certain details of construction and combinations of parts, as will be hereinafter described, and pointed out in the claims.

In carrying out my invention as herein shown I employ two corresponding foothold-plates A A, having differentiated edges, each having one edge serrated to form a rat-trap foothold A' and each having one edge provided with a rubber bar A² to form a rubber-bar foothold. As shown, the rubber bars A² are secured in place by their provision with ribs A³, which are inserted into skeleton-like pockets formed by cutting the edges of the plates transversely, so as to produce retaining-fingers A⁴, which are alternately set in opposite directions to form skeleton rib-receiving pockets, as shown in Fig. 2. Each of the plates is also provided with two pairs of retaining-horns A⁵ A⁵ and A⁶ A⁶, the horns A⁵ 45 being located at the ends of the rat-trap foot-

hold and the horns A⁶ at the ends of the rubber-bar foothold. Each of the plates is also constructed with two transversely-arranged slots A⁷ A⁷, corresponding to each other and located on opposite sides of the longitudinal 55 centers of the plates.

As herein shown, the pedal-frame consists of a hub B and four laterally-projecting arms B', arranged in two pairs, located opposite each other and extending in opposite directions. The hub B receives the pedal-pin C, which may be of any approved construction and to which the frame may be applied in any suitable manner. The outer ends of the arms B' are formed with longitudinally-threaded holes for the reception of retaining-screws D, the shanks of which pass through the slots A⁷ and which secure the foothold-plates to the arms of the frame, as shown in Fig. 2. Friction-springs E, located between 70 the plates and the arms, hold the plates in position. It will be understood from the foregoing that the plates may be adjusted with respect to the frame within the limits fixed by the length of the slots A⁷, which are long 75 enough to permit the plates to be sufficiently moved to shift the center of gravity of the pedal, so as to cause it to balance with the rat-trap footholds of its plates uppermost or with the rubber-bar footholds of its plates 80 uppermost. If, therefore, it is desired to use the pedal as a rat-trap pedal, the plates are pushed downward against the tension of the springs E and by means of their rat-trap-foothold edges, so that the center of gravity 85 of the pedal will fall below the pedal-pin and be on the side adjacent to the rubber-bar footholds. Under these conditions the rat-trap footholds of the foothold-plates will be uppermost and the pedal will be balanced in 90 that position. By pushing the plates in the opposite direction the center of gravity will be transferred to the side of the pedal adjacent to the rat-trap footholds of the foothold-plates and the pedal will be balanced with its 95 rubber-bar edges uppermost. The shifting of the plates, as described, is conveniently effected and may, if desired, be done by the rider when he is propelling the machine.

When the pedal is adjusted to use the rat- 100

trap footholds, it is as effective as any rat-trap pedal, while, on the other hand, if it is adjusted to use the rubber-bar footholds it is as effective as any rubber-bar pedal. I thus combine by my invention pedals of the two types in one pedal to obvious advantage.

It is apparent that in carrying out my invention some changes from the construction herein shown and described may be made. Thus the particular form of the foothold-plates and their respective edges and the form of the frame may be changed. I do not therefore limit myself to the exact construction shown and described, but hold myself at liberty to make such changes and alterations as fairly fall within the spirit and scope of my invention.

Having fully described my invention, what I claim as new, and desire to secure by Letters Patent, is—

1. In a convertible balanced pedal, the combination with a pedal-frame comprising a hub, and arms projecting laterally therefrom, of foothold-plates having their edges differentiated in their holding character, applied to the outer ends of the said arms and movable with respect thereto for shifting the center of gravity in the pedal to cause the same to bal-

ance with either edge of its footholds uppermost.

2. In a convertible bicycle-pedal, the combination with a frame comprising a hub, and arms projecting laterally therefrom, of two foothold-plates having their edges differentiated to form rat-trap and rubber-bar footholds, and applied to the outer ends of the said arms with respect to which they are movable for shifting the center of gravity in the pedal so as to balance it with either the rat-trap or rubber-bar edges of its plates uppermost.

3. In a convertible balanced bicycle-pedal, the combination with the frame thereof, of two foothold-plates formed with slots, means for securing the plates through their slots to the frame, and springs interposed between the plates and the frame for normally restraining the movement of the plates, substantially as described.

In testimony whereof I have signed this specification in the presence of two subscribing witnesses.

JOSEPH P. LAVIGNE.
